UNITED STATES PATENT OFFICE.

LOU OBSTFIELD, OF NEW YORK, N. Y., ASSIGNOR TO MARKWELL MANUFACTURING CO.,
INC., OF NEW YORK, N. Y., A CORPORATION OF NEW YORK.

CUSHION CAP FOR STAPLING MACHINES AND THE LIKE.

Application filed April 6, 1922. Serial No. 550,048.

To all whom it may concern:

Be it known that I, LOU OBSTFIELD, a citizen of the United States, and a resident of the borough of Manhattan, city, county, and 5 State of New York, have invented an Improvement in Cushion Caps for Stapling Machines and the like, of which the following is a specification.

My present invention relates to cushion 10 caps for stapling machines and the like and aims to provide devices of the general character referred to which shall be simple in construction, which shall be readily and conveniently applicable to the devices with 15 which the same are intended to be used, which shall be economical to manufacture and readily marketable, and which shall admirably and successfully serve the purpose for which they are intended.

20 By way of example, I shall in the accompanying specification describe and in the annexed drawing show several illustrative embodiments of my present invention, it being, however, clearly understood that my invention is not limited to the embodiments 25 thereof which are herein shown and described for purposes of illustration only.

Referring to the drawings,

Figure 1 is a view in side elevation of one 30 embodiment of my present invention shown as applied to a common type of stapling machine;

Figure 2 is a cross-sectional view of the 35 cushion cap shown in Figure 1;

Figures 3 and 4 are similar views of two other cushion caps of modified construction; and

Figures 5 and 6 are longitudinal sectional 40 views, along lines 5-5 and 6-6 of Figures 2 and 4, respectively.

Referring first to the device illustrated in Figures 1, 2 and 5 of the drawing, 10 indicates the main body portion of an ordinary type of stapling machine, having the plunger 11 maintained in raised or inoperative 45 position by the spring 12, and provided at its upper end with the operating head 13.

Ordinarily the operating head 13 is hit or struck by the open palm of the person operating the machine, thus bringing the plunger 11, against the action of the spring 12, into the operating position to sever and apply one of the staples in the machine. 10. This act often causes considerable discom-

fort or even pain to the hand of the person 55 operating the machine. This is particularly the case where the device is a part of the ordinary office equipment and is operated by young women for whom the operation of the machine is often a distasteful and uncomfortable affair.

By means of the cushion cap of the present invention, I render the operation of the machine comfortable and even improve such 65 operation, since the operating head may now be struck a full, square blow with the certainty that the staple will be properly severed and applied, and with the further certainty that the hand of the operator will not be hurt or injured by the operating blow. 70

For this purpose, I provide a cushion cap generally designated by reference character 14. This cushion cap comprises an upper dome-shaped member 15, having an inner dome-shaped face 16, and a lower lip-shaped member 17, attached to, and preferably integral with, the upper member 15. The member 17 is preferably obliquely and inwardly turned or inclined. It will also be noted, as more clearly shown in Figures 1 80 and 2 of the drawing, that the thickness of the rubber or other resilient material of which the cushion cap 14 is preferably made, diminishes from the center of the upper dome-shaped member outwardly and obliquely down to the inner edge of the lip-shaped member 17. 85

In order to render the device even more efficient for the purpose of preventing injury to the hand of the person operating the machine, I prefer to provide the upper dome-shaped member with auxiliary pneumatic cushioning means. Such auxiliary pneumatic cushioning means may comprise a substantially centrally disposed indentation 18, providing an air pocket or cushion 90 between the upper surface of the operating head 13 and the inner dome-shaped face 16 of the upper member 15. 95

If desired, the auxiliary pneumatic cushioning means may comprise an air cell 18' provided between an inner layer 19' and the inner face 16' of the upper dome-shaped member 15', as more clearly shown in Figure 4 of the drawing. On the other hand, 100 the auxiliary pneumatic cushioning means may be altogether omitted, as more clearly shown in Figure 3 of the drawing where the 105

upper dome-shaped member 15" is shown as being without any auxiliary pneumatic cushioning means.

- 5 The manner of using the device and the advantages of the device in use may briefly be summarized as follows: By reason of the construction of the cushion caps shown, the cap may be readily and conveniently applied to the operating head of the stapling 10 or similar machine. This application of the cushion cap to the operating head of the stapling machine is facilitated by the shape and construction of the lower lip-shaped member 17. This member is of comparatively 15 light-weight, flexible material, especially as compared with the comparatively heavy resilient material, such as rubber, of which the upper dome-shaped member 15, or its equivalent, is preferably formed.
- 20 The dome-shaped member 15, or its equivalent, especially by reason of its construction, which provides the greatest amount of resilient material substantially at the center of the dome-shaped member, and espe-

cially where auxiliary pneumatic cushioning means, such as the air cushion 18 or the air cell 18', is provided, serves to cushion the blow delivered by the hand of the operator to the operating head 13 of the stapling or other machine.

30 The device is simple but very efficient, may be easily manufactured, is easily applied, and is very satisfactory in use.

35 What I claim is:

A cushion cap for stapling machines and the like comprising an upper dome-shaped cushioning member having an inner dome-shaped face and an obliquely and inwardly disposed peripheral member, said upper member being provided with auxiliary pneumatic cushioning means in the form of a 40 substantially centrally disposed indentation on the inner face thereof.

45 In testimony whereof, I have signed my name to this specification this 27 day of March 1922.

LOU OBSTFELD.
